UNITED STATES PATENT OFFICE.

CHARLES M. BEARD, OF ELROY, WISCONSIN, ASSIGNOR OF ONE-HALF TO
MERWIN R. DAVENPORT, OF BARABOO, WISCONSIN.

DESIGN FOR A LACING-STUD.

SPECIFICATION forming part of Design No. 30,078, dated January 31, 1899.

Application filed January 9, 1899. Serial No. 701,674. Term of patent 14 years.

To all whom it may concern:

Be it known that I, CHARLES M. BEARD, a citizen of the United States, residing at Elroy, in the county of Juneau and State of Wisconsin, have invented and produced a new and original Design for a Lacing-Stud; and I do hereby declare the following to be a full, clear, and exact description of the same, reference being had to the accompanying drawings, forming a part thereof.

Figure 1 represents a perspective view, on an enlarged scale, of a lacing-stud, showing my new design. Fig. 2 is a side view of the same. Fig. 3 is a top view of the same.

As shown in the drawings, the leading feature of my design consists in a knob-like head having flat sides with a perforation therethrough, said head resting on a collar of oval form, and under said collar a short cylindrical stem or stud pendent eccentrically therefrom.

A is the knob-like head, having its front

portion substantially vertical and its rear in the form of a relatively long incline *a*. The sides of said head are flat and substantially parallel with each other, and through said sides and head there is a perforation *b*, adjacent to its front portion. Said head rests upon a flat collar C, the periphery of which is of substantially oval form. Under said collar there is a short cylindrical stem or stud *d*, located in the long axis of the collar, but on one side of its center and directly under the long incline *a* of the head.

What I claim is—

The design for a lacing-stud substantially as herein shown and described.

In testimony whereof I affix my signature in presence of two witnesses.

CHARLES M. BEARD.
